UNITED STATES PATENT OFFICE.

JOSEPH GOULBOURN, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-TRIMMING MACHINE.

1,270,511.

Specification of Letters Patent. Patented June 25, 1918.

Application filed May 11, 1915. Serial No. 27,369.

To all whom it may concern:

Be it known that I, JOSEPH GOULBOURN, a subject of the King of England, residing at Leicester, Leicestershire, England, have 5 invented certain Improvements in Heel-Trimming Machines, of which the following description, in connection with the accompanying drawings, is a specification, like reference characters on the drawings indicating 10 like parts in the several figures.

This invention relates to machines for trimming the heels of boots and shoes, and particularly to means for positioning the shoe with reference to the heel trimming 15 cutter.

In a type of heel trimming machine in common use the position of the shoe with reference to the cutter is controlled by means of guiding devices which engage the shoe in 20 the rand crease and at the edge of the toplift, and the toplift guide is arranged with reference to a tread rest for the heel to present a narrow guiding surface with which the edge of the toplift is engaged. It has been 25 found advantageous in the construction of such devices to include provision for adjustment to vary the width of the effective guiding surface of the toplift guide to accommodate variations in the thickness of the toplift on shoes of different sizes or styles. Such adjustment is particularly advantageous 30 in trimming heels some of which are provided with rubber toplifts, since toplifts of this material are usually of greater thickness 35 than leather toplifts, and in view moreover of the fact that the rubber is more likely to slip on the guide, it is particularly desirable in trimming heels provided with rubber toplifts to increase the width of the toplift 40 guiding surface. In providing for such adjustment it is important, in order to avoid loss of time and also to insure that the operator shall change the adjustment whenever 45 such a change is desirable for the best results on the work, to arrange the adjusting means for ready manipulation by the operator to effect a quick and certain adjustment of the parts.

An important object of this invention accordingly is to effect improvements in heel 50 positioning means for heel trimming machines, and particularly to provide a construction in which a ready and quick adjust-

ment may be effected to vary the width of the effective guiding surface of the toplift 55 guide.

To the above and other ends, a feature of the invention consists in shoe positioning means including a guide arranged to be engaged by the edge of the toplift of a shoe 60 heel for positioning the heel with reference to the cutter, said means being constructed and arranged for adjustment to vary the width of the effective guiding surface of the toplift guide, and unitary mechanism for 65 effecting a quick adjustment of said means.

In the illustrated construction, in accordance with a feature of the invention, the positioning means is arranged for substantially translational movement to adjust the 70 width of the effective guiding surface of the toplift guide in such manner as to insure a substantially uniform width of guiding surface around the periphery of the toplift guide in any position of adjustment. 75

A further feature consists in shoe positioning means constructed and arranged for adjustment to vary the width of the effective guiding surface of the toplift guide, and means for insuring a substantially uniform 80 width of said guiding surface throughout the peripheral extent of the guide for all positions of said adjustment. In the construction herein shown the shoe positioning means comprises a toplift guide and a tread rest adjustable with reference to said guide 85 to vary the width of the effective guiding surface of the guide, with means for maintaining the tread rest in substantially the same angular relation to the guide in all 90 positions of its adjustment.

The above and other features of the invention, including certain details of construction and combinations of parts, will now be described with reference to the accompanying 95 drawings which embody a preferred form of the invention, and will be pointed out in the claims.

In the drawings,

Figure 1 is a front view of the upper portion of a heel trimming machine in which the invention is embodied;

Fig. 2 shows a portion of the shoe positioning mechanism detached, including the relatively adjustable toplift guide and tread 105 rest;

Fig. 3 is a cross-section through a portion of the device, and

Fig. 4 is a detail view of a portion of the adjusting means.

5 The heel trimming machine shown comprises a rotary cutter 2 driven by a shaft 4 which is mounted in bearings on the frame 6. Mounted upon the front of the machine is a bracket 8 which carries a portion of the shoe 10 positioning mechanism including the toplift guide 10, this bracket being adjustable longitudinally of the cutter axis to vary the position of the toplift guide longitudinally of the cutter. The bracket is held in adjusted 15 position by means of a clamping screw 12. In order to permit adjustment of the toplift guide toward or from the cutter in a plane transverse to the cutter axis the bracket 8 is provided with a slideway 13 to receive a dove-tailed slide 14 to which the guide 10 is secured. The slide 14 is adjustable by means of a screw 16 threaded in a projection 18 on the slide and journaled in a plate 20 on the front of the bracket 8. Turning of the 25 screw thus serves to vary the position of the slide 14 and consequently to adjust the toplift guide transversely of the cutter axis. In order to guard against accidental change of adjustment through turning of the screw a 30 spring 22 is arranged between the plate 20 and the slide 14 to increase the frictional resistance to turning of the screw.

The guide 10 is curved as usual to conform substantially to the curvature of the cutter. Positioned adjacent to the convex surface of the guide is a member 24 which serves as a tread rest for the toplift and in the construction illustrated is adjustable with reference to the guide 10 to vary the 40 width of the effective guiding surface of said guide. The tread rest 24 is arranged for adjustment on a line substantially parallel to the axis of the cutter, and in order to maintain the same angular relation between this rest and the guide 10 in all 45 positions of adjustment the rest is provided with a shank 26 arranged to slide in a socket 28 formed in the member 14. In order to permit a quick adjustment to vary the width 50 of the guiding surface of the toplift guide for different shoes the shank 26 is provided with a slot 30 in which is positioned a pin 32 mounted eccentrically on a spindle 34, the spindle being rotatable in a bearing 36 in the slide 14 by means of a handle 38.

It will be readily seen that with this arrangement all that the operator is required to do, in order to effect any desired variation in the width of the guiding surface of 60 the toplift guide, is to make a slight turn of the spindle 34 by means of the handle 38. Practically no time, therefore, will be lost in making changes of adjustment to meet varying conditions of the work. At the 65 same time, moreover, the arrangement in-

sures that for all adjustments the tread rest 24 and the guide 10 will be maintained in the same angular relation so that the width of the guiding surface of the toplift guide will be uniform throughout its peripheral 70 extent. In order to insure against changes of adjustment through accidental displacement of the handle 38 the device includes also a set screw 40 which is arranged to bear upon the shank 26 and may be tightened to 75 secure the tread rest in adjusted position.

Having described the invention, what I claim as new and desire to secure by Letters Patent of the United States is:—

1. In a heel trimming machine, the combination with a heel trimming cutter, of shoe positioning means including a guide for engaging the edge of the toplift to determine the position of the heel with reference to the cutter, said positioning means having a portion arranged for substantially translational movement to adjust the width of the effective guiding surface of the toplift guide, and said parts being constructed and arranged to insure a substantially uniform width of said guiding surface throughout the peripheral extent of the toplift guide for any position of said adjustment. 80

2. In a heel trimming machine, the combination with a rotary cutter, of a guide arranged to be engaged by the edge of the toplift for positioning the heel with reference to the cutter, a tread rest for the heel, said toplift guide and tread rest being relatively adjustable to vary the width of the 95 effective guiding surface of the toplift guide, and guiding means comprising parts arranged for relative translational movement in substantially parallel relation to the axis of the cutter for maintaining the toplift 100 guide and the tread rest in substantially the same angular relation in all positions of said adjustment.

3. In a heel trimming machine, the combination with a heel trimming cutter, of shoe positioning means including a guide arranged to be engaged by the edge of the toplift for positioning the heel with reference to the cutter, said positioning means having a portion arranged for adjustment to 110 vary the width of the effective guiding surface of the toplift guide, and unitary mechanism connected with said adjustable portion and movable relatively thereto for effecting said adjustment. 115

4. In a heel trimming machine, the combination with a rotary cutter, of a guide arranged to be engaged by the edge of the toplift for positioning the heel with reference to the cutter, a tread rest for the heel, said toplift guide and tread rest being relatively adjustable to vary the width of the effective guiding surface of the toplift guide, unitary means connected with one of said parts and arranged to be readily manipulated by 125 130

the operator for effecting a quick relative adjustment of the parts, and guiding means comprising portions relatively movable on a line substantially parallel to the axis of the cutter for maintaining the toplift guide and the tread rest in substantially the same angular relation in all positions of said adjustment.

5. In a heel trimming machine, the combination with a heel trimming cutter, of a guide arranged to be engaged by the edge of the toplift for positioning the heel with reference to the cutter, a tread rest adjustable with reference to said guide to vary 10 the width of the effective guiding surface of the guide, means independent of the tread rest and connected thereto for adjusting said rest, and means for maintaining the tread rest in the same angular relation to the guide 15 in all positions of its adjustment.

6. In a heel trimming machine, the combination with a heel trimming cutter, of a guide arranged to be engaged by the edge of the toplift for positioning the heel with reference to the cutter, a tread rest adjustable 20 with reference to said guide to vary the width of the effective guiding surface of the guide, and means for adjusting the tread rest comprising a rotatable spindle having a pin 25 mounted eccentrically thereon, said pin having connection with said rest for effecting movement of the rest upon rotation of the spindle.

7. In a heel trimming machine, the combination with a rotary cutter, of a guide arranged to be engaged by the edge of the toplift for positioning the heel with reference to the cutter, a tread rest adjustable with reference to said guide to vary the width 30 of the effective guiding surface of the guide, said tread rest having a shank extending in substantially parallel relation to the axis of the cutter, means for guiding said shank to maintain the tread rest in substantially the 35 same angular relation to the toplift guide in all positions of adjustment of said rest, said shank having a slot formed therein, and a rotatable adjusting spindle having a pin

mounted eccentrically thereon and engaging in said slot.

8. In a heel trimming machine, the combination with a rotary cutter, of a guide arranged to be engaged by the edge of the toplift for positioning the heel with reference to the cutter, a tread rest adjustable 50 with reference to said guide to vary the width of the effective guiding surface of the guide, a shank extending from the tread rest and having a slot formed therein, a rotatable adjusting spindle having a pin 55 mounted eccentrically thereon and engaging in said slot, a handle for effecting rotation of the spindle to adjust the tread rest, and additional means for securing the tread rest in adjusted position.

9. In a heel trimming machine, the combination with a heel trimming cutter, of a guide arranged to be engaged by the edge of the toplift for positioning the heel with reference to the cutter, a tread rest adjustable 60 with reference to said guide to vary the width of the effective guiding surface of the guide, said tread rest having a substantially straight shank, means for guiding said shank to maintain the tread rest in substantially 65 the same angular relation to the toplift guide in all positions of adjustment of said rest, and means for engaging said shank to effect the adjustment of the rest.

10. In a heel trimming machine, the combination with a rotary cutter, of a guide arranged to be engaged by the edge of the toplift for positioning the heel with reference to the cutter, a tread rest adjustable with reference to said guide to vary the width of the effective guiding surface of the guide, said tread rest having a shank extending in substantially parallel relation to the axis of the cutter, and means for guiding said shank to maintain the tread rest in substantially 70 the same angular relation to the toplift guide in all positions of adjustment of said rest.

In testimony whereof I have signed my name to this specification.

JOSEPH GOULDBOURN.
